UNITED STATES PATENT OFFICE.

EDWARD C. WATTERS, OF KANSAS CITY, MISSOURI.

SLIP-JOINT.

1,119,130.

Specification of Letters Patent.

Patented Dec. 1, 1914.

Application filed June 16, 1913. Serial No. 773,902.

To all whom it may concern:

Be it known that I, EDWARD C. WATTERS, a citizen of the United States, residing at Kansas City, in the county of Jackson and State of Missouri, have invented certain new and useful Improvements in Slip-Joints; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to slip joints, and more particularly to a joint for use in connection with a dressmaker's square, wherein it is desirable to provide two or more rules or pattern members for each square, in order to adapt the square for different uses, the principal object of the invention being to provide a joint having members adapted for holding the parts of the square rigidly, and whereby the members may be easily and quickly connected or disconnected. In accomplishing this object I have provided improved details of structure, the preferred form of which is illustrated in the accompanying drawings, wherein:—

Figure I is a plan view of a dressmaker's square provided with a slip joint constructed according to my invention. Fig. II is an enlarged plan view of the joint showing the members partly disconnected in dotted lines. Fig. III is an end view of the joint. Fig. IV is an enlarged section on the line IV—IV, Fig. II. Fig. V is a detail perspective view of the joint member 17. Fig. VI is a similar view of the ear 27.

Referring more in detail to the parts:— 1 designates the body of a square, and 2 one of the removable members which may be used in connection with the body, both of the parts being provided with co-operating slide joint members of the following construction:

Mounted on the body member 1 is a joint socket member 3, which is preferably formed in two sections or halves, each of which has 50 a facing channel 4 and edge rail 5, the latter having a lip 6 overhanging the channel part, which, when the members are in assembled relation, forms a dovetailed groove for carrying the rib of the mating joint section. 55 The outer edge of the socket member 3 is down-cut to provide the fins 7, which pro-

ject laterally from the body of the member into a slot 8 in the edge of the section 1 of the square, the fin being cut away between its ends to form the end wings 9, having 50 edges shaped to conform to the shape of the square section 1. The halves or parts of the socket member 3 are rigidly and permanently connected by rivets 11, and the socket member is fixed to the body of the square 55 by other rivets 12 passing through the material of which the square is formed, and through the fin wings 9. In order to further secure the socket member to the body of the square and impart rigidity to the 70 joint, I provide ears 13, each of which comprises a body portion which is adapted to seat in a countersunk recess 14 in the body section 1, and has a rail 15 at its outer edge seated on the projecting joint fin 7. 75

The joint member for the body 2 comprises a body portion 17 having a neck 18 and head 19, adapted respectively for sliding travel between the edge rails 5 and in the socket 4 of the mating joint section 1, the 80 head having edge portions 20 for projection into the dove-tailed grooves in said mating section to steady the parts when in assembled relation. The body portion 17 is provided with a fin 21 having wings 22 which 85 are similar respectively to the fin and wings on the mating joint section, and which project into a slot 23 in the removable member of the square, and are rigidly connected therewith by rivets 24. The body 17 of the 90 joint member has a groove 25 between its ends and extending along the fin 21, for receiving the inner edge of an ear 27 which is 95 adapted to lie within a countersunk recess 28 in the removable member 2, and is fixed in position and permanently secured to the body 2 and fin 21 by rivets 29 which extend through apertures 30 in the ear into the body member and fin.

In order to firmly seat the ears 27, I prefer to cut the ends of the groove 25 in outwardly converging planes, so that when the rib 26 is seated in its groove it will be locked in place by the abutting edges of the groove. 100

While I do not wish to limit myself to such construction, it is apparent that the joint is particularly adapted for a square, constructed of different layers of material, or what is known as a veneer construction, as with such a construction, the inner portions of the bodies may be cut away to form 105 the joint grooves much more conveniently 110

than if it were necessary to split the relatively thin material.

It is apparent that with the parts constructed and assembled as described, the 5 separate members of the square may be easily and quickly assembled or taken apart, so that a single body member may be provided with a plurality of heads of different patterns, or the like, so that it is not necessary for a dressmaker to have a separate 10 complete square for each pattern. It is also apparent that this construction is particularly adaptable for squares, or the like, which are, of necessity, made of thin material, as the flange and ear attachments will provide rigid connection between the joint 15 and body portions of the square. The use of the invention is clearly apparent, as with the parts properly assembled, one of the 20 joint members may be slipped into and from the other, as desired.

Having thus described my invention, what I claim as new therein, and desire to secure by Letters-Patent, is:—

25 1. A slip joint, comprising head and socket members, each having a fin at its inner edge, and ears adapted for coöperation with said members to attach same to a carrying structure, the head member having a 30 groove adjacent its fin, and the head ear

having a portion for seating in said groove, substantially as set forth.

2. A slip joint, comprising head and socket members, each having a fin at its inner edge, and an ear adapted for coöperation with said members to attach same to a carrying structure, the ears for the socket section having shoulders at their outer edges for support on the fin of said section. 35

3. A slip joint, comprising socket and head members, each having an edge fin provided with enlarged end wings, and ears having their outer edges supported on said members, and having body portions overlying the exposed areas between the fin 40 45 wings.

4. The combination with separate square sections, each having a grooved end, of socket and head joint sections having fins projected into the slots in the square sections respectively, and ears on said joint sections countersunk in opposite faces of the square sections. 50

In testimony whereof I affix my signature in presence of two witnesses.

EDWARD C. WATTERS.
